Primary Examiner — George D. Kirschbaum*Assistant Examiner* — Darcey E Gottschalk(74) *Attorney, Agent, or Firm* — Banner & Witcoff, Ltd.(57) **CLAIM**

The ornamental design for a lid, as shown and described.

DESCRIPTION

FIG. 1 is a top, front, left perspective view of a lid showing our new design;

FIG. 2 is a bottom, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines immediately adjacent to the shaded area represent unclaimed boundaries of the design. The broken lines showing the remainder of the lid represent unclaimed subject matter and form no part of the claimed design.

1 Claim, 7 Drawing Sheets# US D856,748 S
